M. HARRIS,
COMBINATION LETTER SHEET AND ENVELOP,
APPLICATION FILED AUG. 28, 1918.

1,313,293.

Patented Aug. 19, 1919.

UNITED STATES PATENT OFFICE.

MARK HARRIS, OF NEW YORK, N. Y.

COMBINATION LETTER-SHEET AND ENVELOP.

1,313,293.

Specification of Letters Patent.

Patented Aug. 19, 1919.

Application filed August 28, 1918. Serial No. 251,743.

To all whom it may concern:

Be it known that I, MARK HARRIS, a citizen of the United States, and residing at New York, in the county of New York and 5 State of New York, have invented certain new and useful Improvements in Combination Letter-Sheets and Envelops, of which the following is a specification, such as will enable those skilled in the art to which it 10 appertains to make and use the same.

This invention relates to combination letter sheets and envelops designed to be used in personal and all business correspondence, such as letter heads, invoices, 15 checks and the like; and the object of the invention is to simplify the form and construction of such devices so as to reduce the cost of the manufacture of the same; a further object being to provide a folding 20 pocket flap at one end of a sheet from which a combination letter sheet and envelop is made, the width of said flap being such as to facilitate the printing of the return card in the upper left hand corner of the flap 25 when folded which return card will appear in the upper left hand corner of the envelop formed by folding the sheet as hereinafter set out; and a still further object being to so construct the combination sheet as to facilitate 30 the printing of the return card and the title to the letter head in one operation; and with these and other objects in view the invention consists in a device of the class and for the purpose specified, constructed 35 and operating as hereinafter described and claimed.

The invention described and claimed herein is an improvement on that described and claimed in a prior U. S. application for 40 a patent filed by me September 15, 1917, Serial No. 191,649, and is fully disclosed in the following specification, of which the accompanying drawing forms a part, in which the separate parts of my improvement are designated by suitable reference characters in 45 each of the views and in which:—

Figure 1 is a plan view of a blank from which one of my improved combination letter sheets and envelops are formed;

50 Fig. 2 a view similar to Fig. 1 but showing the pocket flap folded and indicating the method of printing the sheet;

Fig. 3 a view showing the sheet completely folded into envelop form prior to 55 sealing the same;

Fig. 4 a view of the envelop completely

sealed and addressed, and ready for mailing; and,

Fig. 5 a view of the letter sheet when opened from the position shown in Fig. 4. 60

In the practice of my invention I provide a combination letter sheet and envelop 10, and in the drawing I have shown such sheet of a business letter head form which consists of a main body portion 11, at one 65 side of which are two members 12 and 13 foldable onto each other and onto the main body portion on the score lines 14 and 15. The opposite side edge of the main body portion 11 is provided with a pocket flap 70 16 foldable upon the body portion on a score line 17.

Inwardly of the opposite side edges 18 and 19 of the sheet 10, or the body portion 11, members 12 and 13 and flap 16 thereof, 75 are parallel rows of perforations 20 and 21 respectively, which form, at said side edges thereof, parts 22, 23, 24 and 25 respectively, which are adapted to be torn off in opening the envelop as hereinafter described. The 80 parts 22 of the body portion 11 are also provided with outwardly extending sealing flaps 26, the corner portions of which are beveled as shown at 27, which flaps are of less width than the parts 22. 85

When the sheet 10 is blank as shown in Fig. 1 and designed to be used as a business letter sheet, the pocket flap 16 is folded inwardly upon the body portion 11 as shown in Fig. 2, and said sheet when in such position may be passed through a suitable printing apparatus to print in one operation, the return card as indicated at 28 in Fig. 2 and the title to the letter sheet as shown at 29, and such other advertising matter or 90 printed matter that may be desired to be applied to said sheet. 95

It will be noted that the sheet is of such construction as to facilitate the passage thereof through a typewriter or similar machine in writing the desired letter upon the sheet, and in folding the sheet prior to mailing the member 13 is first folded on the score line 14 inwardly upon the member 12, and said members thus folded are folded 100 upon the score line 15 inwardly upon the body portion 11 with the free edge of the members 12—13 beneath the folding pocket flap 16 into the position shown in Fig. 3, after which the sealing flaps 26 may be 110 moistened and folded inwardly upon the parts 23 and 25 of the member 12 and flap

16 to seal the sheet thus folded to form the envelop, and this position of the sheet is shown in Fig. 4.

It will be understood that the envelop 5 may be addressed to the desired party when in the position shown in Fig. 4, or the address may be applied to the back of the member 12 when the sheet is in its extended position as shown in Fig. 2, and the party 10 receiving the letter and desiring to read the contents thereof, simply tears off the parts 22 to 25 inclusive, at the opposite sides of the body portion 11, members 12-13 and flap 16 on the lines of perforations 20-21, 15 which will leave a continuous and unobstructed sheet 30 as shown in Fig. 5 of the drawing, containing only the letter printed, typewritten or otherwise applied to the sheet and the printed return card 28 on 20 the back of the flap 16, which return card is not shown in Fig. 5.

It will be apparent that my improved combination letter sheet and envelop may be used in all kinds and classes of correspondence, such as personal and business 25 correspondence, and may be made up into check and invoice form in all of which uses the envelop or the material thereof is saved, which consequently results in a great saving 30 of paper. Again, the cost of printing is reduced one-half by reason of the fact that the return card and title to the letter sheet is printed in one operation.

My improved combination letter sheet 35 and envelop has all the qualities and advantages of independent letter sheets and envelopes as an absolutely sealed envelop is obtained when the parts of the sheet are folded into the position shown in Fig. 4, 40 and with my construction I produce an envelop which may be easily opened and which will avoid the destruction of independent sheets placed within the envelop and independent of the main sheet, and 45 again, it will be impossible for others than the party to whom the letter is addressed to open the envelop without showing evidence of such action.

While I have shown but one form of let-

ter sheet and envelop, it will be understood 50 that my invention is not limited to this form of device and various changes in and modifications of the details of construction herein shown and described may be made, within the scope of the appended claim, 55 without departing from the spirit of my invention or sacrificing its advantages.

Having fully described my invention, what I claim as new and desire to secure by Letters Patent, is:—

A combination letter sheet and envelop blank consisting of a body portion having on one side edge thereof an ungummed pocket flap of materially less width than the body portion and folded inwardly thereon, said body portion being provided at its opposite side edge with a member adapted to be folded inwardly upon said body portion, the free edge of said member when folded being under the pocket flap and the 70 transverse width of said member and said pocket flap being the same, the body portion being of greater transverse dimensions than the other parts to provide unitary sealing flaps at the opposite sides thereof which 75 are adapted to be folded inwardly upon said member and said pocket flap to form a sealed envelop, and the body portion, said member and the pocket flap being provided inwardly of the side edges thereof and inwardly of said sealing flaps with parallel 80 rows of perforations which form strips extending the full length of the body portion, member and pocket flap which are adapted to be torn off in opening the envelop to 85 leave a plain and unobstructed letter sheet when open, said blank before being folded for use as an envelop having the pocket flap folded down upon the body portion and certain printed matter then placed thereon. 90

In testimony that I claim the foregoing as my invention I have signed my name in presence of the subscribing witnesses this 27th day of August, 1918.

MARK HARRIS.
